UNITED STATES PATENT OFFICE

168,302

FOOTBALL BLOCKING PROTECTOR

Laird B. Holt, Palo Alto, Calif.

Application June 29, 1951, Serial No. 15,714

Term of patent 14 years

(Cl. D34—5)

To all whom it may concern:

Be it known that I, Laird B. Holt, a citizen of the United States and a resident of Palo Alto, Santa Clara County, California, have invented a new, original, and ornamental Design for a Football Blocking Protector, of which the following is a specification, reference being had to the accompanying drawing, forming a part thereof.

The dominant portion of my new design is indicated by the solid lines in the drawing.

I claim:

The ornamental design for a football blocking protector, substantially as shown and described.

LAIRD B. HOLT.
